UNITED STATES PATENT OFFICE.

HARRY L. HOWARD, OF LANSING, MICHIGAN.

SHEARS ATTACHMENT FOR PLIERS.

1,321,745.

Specification of Letters Patent.

Patented Nov. 11, 1919.

Application filed April 8, 1919. Serial No. 287,153.

To all whom it may concern:

Be it known that I, HARRY L. HOWARD, a citizen of the United States, residing at Lansing, in the county of Ingham and State 5 of Michigan, have invented certain new and useful Improvements in Shears Attachment for Pliers, of which the following is a specification.

The object of the present invention is to 10 provide an attachment in the form of a shearing device applicable to a conventional tool, such as a pair of pliers.

In brief the idea in mind is to so construct the attachment mentioned that it may 15 be readily slipped upon and secured to the pliers without necessitating any modification of the latter to permit of the combination, and in this way to obtain an additional tool or implement when required which is 20 operable by means of one which is usually at hand or forms a part of nearly every tool kit.

This and such other objects as may hereinafter appear are attained by the novel 25 construction, combination and arrangement of parts to be hereinafter specifically described and claimed. Reference will now be had to the accompanying drawings forming a part of this specification, wherein:

30 Figure 1 is a side elevation showing the application of my device to a pair of pliers;

Fig. 2 is an elevation view of the unitary attachment itself;

Fig. 3 is a top plan view;

35 Fig. 4 is an enlarged perspective view of the seat or clip for receiving the jaw of the pliers; and

Fig. 5 is a perspective view of the spring connecting member for holding the attachment in place upon the pliers.

Throughout the following detail description and on the several figures of the drawings, similar parts are referred to by like reference characters.

45 In the drawing 1 indicates a pair of pliers of conventional form and construction, most commonly known as the long nose slip joint type. While the invention is particularly adapted for application to this style of tool, 50 it will be obvious that its use is not necessarily restricted to this particular construction. In fact, as will be described hereinafter, provision is made for its application to a pair of pliers having different jaw members and for this reason I do not wish to 55 be limited unnecessarily except as required

by the scope of the claims forming a part of this application.

The attachment which forms the subject-matter of this invention is unitary in construction, that is, complete in itself, and consists of a pair of blade members 2, 3 pivoted at one end as indicated at 4. One of the blade members, 2, is provided with an arcuate slot 5, in which a pin 6 mounted 60 in the arm or plate 7 attached to the pivot 4 operates. Each blade member adjacent to its pivot end has secured thereto a jaw-receiving seat or clip 8 more particularly shown in Fig. 4. In the construction of this 65 particular attachment the clip is provided with an elongated slot 9, in which the edge of the blade is riveted so as to securely hold the clip in place. The bottom surface of this clip is preferably serrated as indicated 70 at 10 so as to coöperate with the serrations usually provided on the jaws of the pliers, thereby to prevent slippage. Since the attachment is applicable to pliers of different 75 shapes, the jaws of which may vary in width, I preferably provide some means in the clip 8 for taking up play. In the embodiment shown in the drawings the means consist of bent springs 11 secured to the sides of the clip as shown clearly in Figs. 80 8 and 4. Any other desired means may be employed for this purpose within the purview of this invention. The attachment is held in place, as shown in Fig. 1, by means of resilient connecting members, one of 85 90 which is shown in Fig. 5, the same consisting of a spring 12 and a U-shaped gripping element 13, the latter being engageable over that portion of the jaw which is attenuated just in rear of the nose portion, the shoulder 14 of which prevents the displacement of the connecting member when it is attached in place as shown in Fig. 1.

In order to provide for the application of this attachment to pliers, for example, of the 95 short nose type, each blade is formed with a slot 15, one edge of which is provided with depressions as indicated at 16 to receive the connecting end of the spring 12. In other words, where the jaw member is 100 of the type last mentioned the end of the spring is engaged in one of the depressions 16 relatively distant from the inner end of the slot so as to bring the end of the jaw or nose against the rear edge 17 of the cut- 110 away portion of the blade.

It will be obvious from the foregoing that

the simple little attachment just described may be carried in one's vest pocket; and wherever it is desired to do work requiring a shearing implement, all that it is necessary to do is to slip the attachment upon a pair of pliers, usually at hand, in the manner shown in the drawing. In this way one is able to take advantage of the leverage which is afforded by handles of the pliers 10 to secure an easily operative shearing implement. From the standpoint of economy it is obvious that the attachment may be cheaply manufactured and yet will perform the desired result very efficiently, because 15 the shearing attachment will cut practically anything from paper to light-weight metals. It is very easily and quickly attached or removed from the pliers and by means of the provision of the spring connecting 20 members tension is placed upon the blades, tending to hold the shearing attachment in open position.

It should be added in conclusion that the device works most advantageously when the 25 slip joint type of pliers is employed and the jaws of said pliers are adjusted to their most open position.

Further, that the provision of a spring 11 at each side of the clips results in the 30 taking up of play equally at each side, or holds the blade members in the proper relative position with respect to the plier jaws. The advantage of such arrangement lies in the fact that this brings the side of a blade 35 in substantially the same plane as the inside surface of the pliers just in rear of the shoulder 14. By the attachment of a shear device to pliers of this form one is able to cut much closer than could be done 40 with the ordinary snips because a far less degree of spreading of the material is caused. That is to say, in cutting a long piece of tin, for instance, the cut metal at one side passes back and up alongside of 45 the inner surface of the thinner portion of the jaw just in rear of the jaw shoulder 14, while the metal at the other side similarly passes back and downwardly along the inner side of the same portion of the other jaw. The facility of cutting action is therefore 50 enhanced in this attachment.

Lastly, the provision of the stop pin 6 is important because it serves to regulate the extent of opening and closing of the plier 55 jaws. On the one hand, if the jaws, and necessarily the blades, are opened too far, the pivot of the pliers may slip, while on the other hand if closed too far there would be a strain on the pivot 4 of the blades or 60 possibility of the cutting edge of the blades coming into contact with the clip 8.

Having thus described my invention, what I claim as new is:

1. The combination with a tool having 65 operable jaws, of a unitary attachment

therefor comprising a pair of members each of which is formed with a jaw-receiving seat applicable to the tool jaws aforesaid, and means detachably engageable with the tool adjacent to the jaws to hold the members in place upon said jaws to be operated thereby. 70

2. The combination with a tool having a pair of jaws and handles for operating the same, of an attachment comprising a pair 75 of coöperating elements each formed with a jaw-receiving clip engageable with the respective tool jaws, and tension means connected to the attachment and removably engageable with the tool to hold the attachment in place, the elements thereof being 80 operable by means of the tool handles aforesaid.

3. The combination with a tool having a pair of jaws, of a shears attachment comprising 85 a pair of blade members arranged to coöperate with the jaws of the tool, and tension means forming a part of the attachment connecting the blade members to the tool and tending to hold the blade members 90 in open position.

4. The combination with a pair of pliers, of a shears attachment therefor comprising a pair of blade members pivotally connected together, means on said blade members in 95 which the jaws of the pliers are received for attachment, and adjustable connecting means intermediate each blade member and the tool holding the attachment in place thereon. 100

5. The combination with a pair of pliers, of a shears attachment therefor comprising a pair of blade members pivotally connected together, means on said blade members in which the jaws of the pliers are received 105 for attachment, adjustable connecting means intermediate each blade member and the tool holding the attachment in place thereon, and means on the jaw-receiving means aforesaid to take up play between said 110 means and the jaws of the pliers.

6. As a new article of manufacture, a shears attachment for pliers comprising a pair of blade members pivotally connected 115 at one end, and a spring connection connected to each blade and engageable with the pliers to hold the attachment in place.

7. As a new article of manufacture, a shears attachment for pliers comprising a pair of blade members pivotally connected 120 at one end, a spring connection connected to each blade and engageable with the pliers to hold the attachment in place, each blade member having a seat to receive the coacting jaw member of the pliers, and means for adjustment of the spring connection to regulate 125 the tension of the latter.

8. The combination with a pair of pliers, of a shears attachment therefor comprising a pair of blade members, means attaching 130

said blade members to the pliers, and stop means on one of the blade members co-acting with the other blade member to regulate the extent of opening and closing of the plier jaws.

9. The combination with a pair of pliers, of a shears attachment therefor comprising a pair of blades pivotally connected and

operable by the pliers, means detachably connecting the attachment to the jaws of 10 the pliers, and stop means coacting with the blades adjacent to their pivot and limiting the movements of the blades produced by the pliers.

In testimony whereof I affix my signature. 15
HARRY L. HOWARD.
